[57] CLAIM

The ornamental design for a bakery container or the like, as shown and described.

DESCRIPTION

FIG. 1 is a top perspective view of a bakery container or the like showing our new design;

FIG. 2 is a top plan view;

FIG. 3 is a bottom plan view showing one-half of the container, the other half being identical to that shown;

FIG. 4 is a side elevational view, the opposite side being identical thereto;

FIG. 5 is an end elevational view, the opposite end being identical thereto;

FIG. 6 is an enlarged scale cross-sectional view taken along line 6—6 of FIG. 4;

FIG. 7 is an enlarged scale cross-sectional view taken along line 7—7 of FIG. 4;

FIG. 8 is an enlarged scale cross-sectional view taken along line 8—8 of FIG. 2; and

FIG. 9 is an enlarged scale cross-sectional view taken along line 9—9 of FIG. 2.
